DESIGN FOR A SPOON OR SIMILAR ARTICLE

Grosvenor N. Allen, Mary Parker Fleming, and Charles A. Bennett, Oneida, N. Y., assignors to Oneida Community, Limited, Oneida, N. Y., a corporation of New York

Application January 31, 1934, Serial No. 50,570

Term of patent 7 years

To all whom it may concern:

Be it known that we, Grosvenor N. Allen, Mary Parker Fleming, and Charles A. Bennett, citizens of the United States, residing at Oneida, county of Madison, State of New York, have invented a new, original, and ornamental Design for a Spoon or Similar Article, of which the following is a specification, reference being had to the accompanying drawing, forming a part thereof, in which—

Figure 1 is a front elevation of a spoon embodying our new design and

Figure 2 is a cross section thereof on the line 2—2 of Figure 1.

The design may be applied to table cutlery, including spoons, forks, knives and the like.

The essential feature of our new design is the ornamentation shown on the handle of the spoon.

We claim:

The ornamental design for a spoon or similar article as shown and described.

In testimony whereof we have hereunto set our hands.
